DOOR OPENER

Frank Brose, Sidney, Mont.

Application September 21, 1931

Serial No. 564,055

5 Claims. (Cl. 268—36)

The invention relates to a door opening device and more especially to foot operated door openers.

The primary object of the invention is the provision of a device or opener of this character, wherein a person on the approach to a doorway can readily operate a foot pedal or stirrup which on downward pressure thereupon will effect the automatic opening of a door or other like swinging closure, so that such person will not be required to manually swing such door or closure to open position, thereby relieving the person from this labor, especially if carrying bundles, goods or the like for delivery within a building or enclosure.

Another object of the invention is the provision of a device or opener of this character, wherein the mechanism for controlling the opening of the door or closure is of novel form, as the door will be controlled to avoid the slamming of the same or striking a person entering a doorway by quick and sudden closing movement of such door or closure.

A further object of the invention is the provision of a device or opener of this character, wherein the same is of great convenience in warehouses and restaurants, and in fact in any place where owners or employees habitually have their arms and hands full or shoulders loaded with goods and wares making it practically impossible to manually handle the door or closure so that by actuating a foot pedal or stirrup the full opening of the door or closure can be effected automatically.

A still further object of the invention is the provision of a device or opener of this character, which is comparatively simple in construction, thoroughly reliable and efficient in operation, strong, durable, automatic of operation, and inexpensive to manufacture and install.

With these and other objects in view the invention consists in the features of construction, combination and arrangement of parts as will be hereinafter more fully described, illustrated in the accompanying drawings, which disclose the preferred embodiment of the invention, and pointed out in the claims hereunto appended.

In the accompanying drawings:

Figure 1 is a horizontal sectional view taken transversely through a door frame and door with the invention applied in accordance therewith.

Figure 2 is a sectional view on the line 2—2 of Figure 1 looking in the direction of the arrow.

Figure 3 is a sectional view on the line 3—3 of Figure 2.

Figure 4 is a fragmentary sectional view on the line 4—4 of Figure 1.

Figure 5 is a sectional view similar to Figure 4 but showing operating means holding door in open position.

Figure 6 is a sectional view on the line 6—6 of Figure 5.

Figure 7 is a sectional view on the line 7—7 of Figure 6.

Figure 8 is a sectional view on the line 8—8 of Figure 2.

Figure 9 is a fragmentary vertical sectional view of door support or pivot bracket.

Similar reference characters indicate corresponding parts throughout the several views in the drawings.

Referring to the drawings in detail A designates generally a doorway or door frame which is of the conventional kind having a swinging door or doors B, only one in this instance being shown and is pivotally mounted vertically for its swinging movement by a bracket 10 having a base extension 11 secured at 12 to the door sill 13, the upper end of this bracket being formed with a pivot ear 14 in which is engaged a pivot 15, the latter connected with a bearing plate 16 set in a notch or cut away portion 17 in the heel edge of the door B.

In axial alignment with the pivot 15 is a turning shaft 18 having the squared upper end 19 which fits in a corresponding opening 20 in a coupling plate 21 mounted on the lower edge of the door B, so that on turning of this shaft the door will be caused to swing and in this manner the door moves to open and closed positions.

The shaft 18 is vertically journaled in a suitable bearing 22 mounted in the base sill 23 of the doorway or frame and extends beneath the flooring 24 for such sill. Loosely engaged on this shaft 18 below the flooring is a stirrup 25 having a yoke 26 formed with upper and lower guides or loops 27 and 28, respectively. The lower end of the shaft 18 has fixed thereto the lower L-bracket 29 while fixed to the bottom face of the flooring 24 is the upper L-bracket 30, the latter being held stationary in alignment with the doorway A or base sill 23. The lower bracket 29 turns with the shaft 18.

Carried by the stirrup 25 on opposite sides of its axis of movement and extending through the guides or loops 27 and 28 are abutment rods 31, these being vertical and parallel with said shaft 18. Active upon the rods 31 are plungers 33, each having the forked head 34 provided with notches 32, the latter serving as seats for the rods 31. The stems 35 of the plungers 33 are slid-

able in the respective brackets 29 and 30. The heads 34 are tensioned by the expansion springs 36 which surround said stems for maintaining the heads in contacting engagement with the rods 31, so that when the door is moved to opening position the same will be tensioned for the swinging thereof closed. The heads 34 are guided in the guides or loops 27 and 28 and when the door B is closed these heads engage both rods 31 to sustain the door in this normal position.

10 Spaced from the shaft 18 and depending from the bottom face of the flooring 24 are inverted U-shaped hangers 37, these being set at an angle to converge toward the doorway A.

15 Vertically slidable through the flooring 24 close to the hangers 37 are foot actuated pedals 38, these being outside and inside with respect to the door B and its door frame A, the posts 39 of these 20 pedals are vertical and slidably fitted in guides 40 on the hangers 37. Operated by each post 39 is a throw rod 41 which has connection with an arm 42 of a rocking shaft 43 journaled horizontally in the companion hanger 37. This shaft 43 has a crank arm 44 pivotally connected with a link 45 which latter is pivoted to the lower end 25 of the post 39 next thereto. The rods 41 are also pivoted to a latching extension 46 of the stirrup 25.

30 The lowermost plunger 33 tensions the door B when pushed by hand to opening position by the forked head 34 eccentrically acting against either rod 31 in the yoke 26 of the stirrup 25. It will be obvious that when the door B is opened by hand the stirrup 25 will not turn with the shaft 18 and the tension of the lower plunger 33 returns the door to closing position.

35 The upper plunger 33 tensions the door B when the same is foot actuated for the opening of said door, and in this manner the latter will return to normal closing position. The upper plunger 40 33 operates identically to the lower plunger when the stirrup 25 is turned, the latter being held fixed to the shaft 18 by the lower plunger at this time, so that said shaft turns with the stirrup 45 for the opening of the door during the actuation of either of the pedals 38.

40 The door B when swung to full opening position on operation of either foot pedal 38 will be momentarily arrested through the medium of a latching bail 47 horizontally disposed and pivoted at 48 in bearings 49, which latter are fixed to the bottom face of the flooring 24 and such bail is tensioned by retractile springs 50 to urge it into contact with the latching extension 46 so that the latter when the door is being opened will engage in either seat 51 in the bail whereby such door B will be momentarily held in opening position. The shaft 18 above the arm 46 has fixed thereto a striker 52 which is adapted for engaging with trip projections 53 formed on and rising from the bail 47 close to the bearings 49 therefor, so that subsequent to the latching of the door by the bail 47 it will be automatically released and returned to closing position. The tension of the plunger 33 is such that the instant the stirrup 25 is released it will have a quick swing so as not to be relatched by the bail 47.

45 What is claimed:

1. The combination with a swinging closure, of

50

a rotatable shaft fixed to the closure for the swinging thereof, a stirrup loose on the shaft, means movable with the shaft and working in the stirrup to tension the closure for closing movement of the same when hand opened, foot operated means connected with the stirrup to move the same for the automatic opening of the closure and means working in the stirrup to tension the closure for closing movement when the stirrup has been moved.

55 2. The combination with a swinging closure, of a rotatable shaft fixed to the closure for the swinging thereof, a stirrup loose on the shaft, means movable with the shaft and working in the stirrup to tension the closure for closing movement of the same when opened, foot operated means connected with the stirrup to move the same for the automatic opening of the closure, means working in the stirrup to tension the closure for closing movement when the stirrup has been moved, and means for momentarily latching the stirrup on the opening of the closure.

60 3. The combination with a swinging closure, of a rotatable shaft fixed to the closure for swinging the same, a stirrup loose on the shaft, means movable with the shaft and working in the stirrup to tension the closure for closing movement of the same when opened by hand, foot operated means connected with the stirrup to move the same for the automatic opening of the closure, means working in the stirrup to tension the closure for closing movement when the stirrup has been moved, means for latching the stirrup on the opening of the closure, and means for releasing the latching means following the latching of the stirrup to permit the closure to swing to closing position.

65 4. The combination with a vertical rotatable shaft for swingingly mounting a closure, of a stirrup mounted on the shaft for independent turning movement thereon, and having upper and lower guides, a bracket fixed to the shaft, a plunger in the bracket, a stationary bracket, a plunger in the latter, abutment rods fixed in the stirrup at opposite sides of its axis of movement, heads working in the guides and on the plungers for engagement with both or either of the rods, means for directing the heads toward the rods and automatically reversing the rotation of the shaft when rotated, and foot operated means connected with the stirrup to turn the same.

70 5. The combination with a vertical rotatable shaft for swinging a closure, of a stirrup mounted on the shaft and movable independently thereof and having upper and lower guides, a bracket fixed to the shaft, a tensioned plunger in the bracket, a stationary bracket, a tensioned plunger in the latter, abutment rods fixed in the stirrup at opposite sides of its axis of movement, heads working in the guides and on the plungers for engagement with said rods and automatically reversing the rotation of the shaft when rotated, foot operated means connected with the stirrup to turn the same, means for latching the stirrup when turned, and means for releasing the stirrup subsequent to the latching thereof.

FRANK BROSE.
